United States Patent Office.

FRANCIS A. STERRY, OF CANTON, MASSACHUSETTS.

Letters Patent No. 67,081, dated July 23, 1867.

IMPROVEMENT IN SPINDLE-STEP.

The Schedule referred to in these Letters Patent and making part of the same.

TO ALL WHOM IT MAY CONCERN:

Be it known that I, FRANCIS A. STERRY, of Canton, in the county of Norfolk, and State of Massachusetts, have invented a new and improved Spindle-Step; and I do hereby declare that the following is a full, clear, and exact description thereof, which will enable others skilled in the art to make and use the same, reference being had to the accompanying drawings forming part of this specification.

The object of my invention is to provide a reversible spindle-step, which may be used in connection with an oil-cup for a much longer period than those now in use, and it consists in uniting either end of the spindle-step to the oil-cup by a screw-joint.

The drawing represents the oil-cup attached to the spindle-step by my improved method, and to a section of a spinning-frame.

A represents the rail of a spinning-frame, and B the spindle-step, which is adjustably secured therein by means of the set-screw D. Upon each end of this step a screw-thread is cut. C is the oil-cup, having through the bottom a hole provided with a female screw which screws upon either end of the step B. E is a spindle, represented in the drawing for the purpose of better illustrating my invention. When one end of the step becomes worn out by the action of the spindle E, the oil-cup is unscrewed, the step reversed, and the oil-cup screwed upon the opposite end. Thus it will be seen that the step is made to last twice as long as those in ordinary use. The upper end of the step B extends up into the cup a short distance, leaving a recess around it, as seen at a. A sufficient quantity of oil is poured into the cup, which finds its way to the bottom, but when the spindle is put in motion the centrifugal force throws it from the centre and step against the sides of the cup, the interior of which represents nearly an inverted cone diminishing in diameter at the top, so that but a small space is left around the spindle. From the sides of the cup the oil is constantly running down towards the bottom of the spindle to be again thrown off and against the sides of the cup. In this way a circulation is kept up, the inclined sides of the cup favoring it, but in the course of this circulation the sediment contained in the oil will lodge in the recess a, from whence it is easily removed. When the spindle is stopped the oil obeys the laws of gravity, and falls back and surrounds the bottom of the spindle.

Having thus described my invention, what I claim therein as new, and desire to secure by Letters Patent, is—

The cup C constructed as described, in combination with the screw-threaded reversible spindle-step B, as herein set forth for the purpose specified.

The above specification of my invention signed by me this 21st day of November, 1866.
